(57) **CLAIM**

The ornamental design for a multiple outlet power strip, as shown and described.

DESCRIPTION

FIG. 1 is a top perspective view showing a new design of a multiple outlet power strip;

FIG. 2 is a left side perspective view thereof;

FIG. 3 is a right side perspective view thereof;

FIG. 4 is a front perspective view thereof; and,

FIG. 5 is a bottom perspective view thereof.

The broken lines shown in FIG. 4 are for illustrative purposes only and form no part of the claimed design.

1 Claim, 5 Drawing Sheets
